CHARLES S. PETERS, OF CUYAHOGA FALLS, OHIO

COMBINATION CHECK AND TAG

Application filed April 13, 1929. Serial No. 354,816.

My invention relates to a combination check and tag, particularly well adapted for use in connection with parked automobiles, while not necessarily restricted to this use.

As is well known, parking spaces and parking garages have recently come into extensive use. The ordinary practice in attempting to check the automobiles parked, is for the attendant to give the owner of the automobile or customer a check having a number thereon, corresponding to the number upon a companion check or ticket, which is attached to the automobile. The companion check is ordinarily placed upon the windshield or some other portion of the automobile and frequently becomes lost, resulting in confusion. It is also well known that the attendants are frequently dishonest and resell the same parking check, thus enabling them to keep the money, which should be paid to the owner of the establishment.

In accordance with my invention, I provide a combination check and tag embodying a tag element and check element, which are originally detachably connected and adapted to be conveniently separated. Prior to separation, the tag element and check element are folded upon each other, and when so folded, the attendant may punch thereon the time that the automobile was left for parking. The tag element and check element carry the same identification numbers. The check element is separated from the tag element and given to the customer while the companion tag element is adapted to be folded transversely upon itself, and is passed about the shank of the door handle of the automobile, and its adjacent portions or ends are secured together by a staple, eyelet or other means. When the customer returns, he presents the check element and the attendant then removes the companion tag element from the handle of the automobile door by tearing the same, which will free it for removal. By thus tearing the companion tag element, it is destroyed for the purpose of resale, thus serving as a check upon the dishonesty of the attendant. I also contemplate forming the combination tag and check device in three sections, thus providing a check element

which may be given to the office, so that the office will have a record of the transaction.

In the accompanying drawings, forming a part of this specification, and in which like numerals are employed to designate like parts throughout the same,

Figure 1 is a perspective view of a tag element, embodied in my invention, showing the same being applied to the shank of a door handle,

Figure 2 is a similar view, showing the tag element folded transversely upon itself, with its adjacent portions stapled together,

Figure 3 is a plan view of the combination check and tag, before the tag elements are separated,

Figure 4 is an end elevation of the same, showing the elements folded longitudinally upon the line of perforation,

Figure 5 is a plan view of a combined check and tag, embodying a modification of the invention, and,

Figure 6 is an end elevation of the same.

In the drawings, wherein for the purpose of illustration, are shown preferred embodiments of my invention, the combination check and tag embodies a tag element 10 and a check element 11, preferably formed of cardboard or the like, and foldable longitudinally upon a perforated line 12. This perforated line secures the tag element 10 and the check element, together, but permits of their convenient separation.

The tag element 10 and check element 11 are provided near one end with the same car identification number 13, as shown. The tag element 10 is preferably provided with a legend "Attach to car", as shown at 14, and the check element 11 is preferably provided with the legend "Customer's check", as shown at 15.

The tag element 10 and check element 11 are provided in their centers with time tables 16, which are identical and embody numerals ranging from 1 to 12, inclusive, as shown at 17, for indicating the hours, and "A. M." and "P. M.", to indicate before or after noon. Each table is also provided with numerals 18, for indicating minutes, preferably intervals of fifteen minutes.

The tag element 10 is cut away adjacent its outer edge, forming an opening 19, which provides a contracted portion, connecting the end portions 20 of the tag element.

In the modification of the invention, as shown in Figures 5 and 6, a third check element 21 is provided, which is originally integral with and carried by the tag element 11, and is foldable longitudinally upon the same along a perforated line 22, whereby the check element 21 may be conveniently torn from the check element 11. The same car identification number 13 is carried by the check element 21.

The check element 21 is provided with a data receiving table, embodying a longitudinal line 23 for receiving the name of the owner or driver of the automobile and a line 24 for receiving his address, and has a transverse line 25 affording a space 26, for the reception of the type of automobile and a space 27 to receive the license plate number. The check element 21 is provided with a legend 28, "Office record", indicating that this check element should be forwarded to the office. A time table 29 is formed upon the central portion of the check element 21, and is identical with the time tables 16 described in connection with sections 10 and 11.

In the use of the first form of combination check and tag, as shown in Figures 1 to 4, inclusive, the attendant folds the elements 10 and 11 longitudinally upon the perforated line 12, and this brings the portions of the time tables 16 into registration. By the use of a suitable punch, the time at which the automobile was left for parking may be indicated. For instance, if the automobile was left at 1:15 P. M., this time is indicated by punching "1" of the numerals 17, and "15" of the numerals 18, and "P. M." The same record is made simultaneously upon both elements 10 and 11. These elements 10 and 11 are now separated by tearing along the line 12, and the check element 11 is given to the customer, while the attendant passes the contracted portion 19 of the tag element 10 about the shank of the door handle, Figure 2, and then secures the ends 20 together by means of a staple 28. I contemplate securing the ends 20 together by any other suitable means, and may provide a seal for the same, whereby it would be impossible to separate such ends without detection. It is thus seen that the tag element is secured to the door handle in a manner to render it impossible that the same be lost or accidentally displaced. When the customer returns for his car, he presents the check element 11 and the attendant locates

the automobile by the numeral 13 thereon, corresponding to the number 13, upon the tag element 10. In removing the tag element 10 from the shank of the door handle, the attendant pulls down upon the ends 20, and readily tears the contracted portion 19. The

tag element 10 is thereby removed and the tearing of the same destroys the tag element, so that it can not be resold. This is an important feature, as it serves as a check against the reselling of used tags.

The use of the modified form of the device shown in Figures 5 and 6, is substantially identical. The elements 10, 11 and 21 are folded longitudinally upon the perforated lines 12 and 22, thus bringing the several time tables into registration, whereby the time may be properly punched in the tables. The several elements are then separated from each other, the element 10 applied to the door handle, as indicated in Figure 2, the element 11 given to the customer, and the element 21 delivered to the office, after the name of the customer, his address, the type of automobile, and license plate number have been properly filled in, upon the same, as provided for in the designated spaces.

Suitable advertisements may be placed upon the tag element 10 and check element 11, and I contemplate using the tag element 10, alone, as an advertising device. In this event, the identification number 13 would be omitted, thus leaving greater space for advertisements. The tag element being applied to the handle of the door would be called to the attention of the driver, upon opening the door, and the advertisements thereon could be read, before or after removal.

It is to be understood that the forms of my invention, herewith shown and described, are to be taken as preferred examples of the same, and that various changes in the shape, size and arrangement of parts, may be resorted to without departing from the spirit of my invention or the scope of the subjoined claims.

Having thus described my invention, I claim:

1. A combination check and tag adapted for use in connection with parked automobiles, comprising a tag element and a check element having a longitudinal line of perforation connecting them so that they may be readily separated, said elements having identification numbers, the tag element having a cut out portion at its longitudinal edge providing an intermediate contracted portion between the ends of the tag element, the tag element being adapted to be folded transversely upon the intermediate contracted portion about the shank of the automobile door handle with the ends disposed upon one side of the handle, and means securing said ends together whereby the intermediate contracted portion will be torn in removing the tag element.

2. A combination check and tag adapted for use in connection with parked automobiles, comprising a tag element and a check element having a line of perforation so that said elements may be folded upon each other on said line, and separated by tearing on said

- line, said elements having identification numbers, said elements also having time tables formed thereon and so co-related that said time tables substantially coincide when said elements are folded upon each other so that
5 the time can be punched upon both tables in one operation, the tag element having a cut out portion at its longitudinal edge providing an intermediate contracted portion between the ends of the tag element, the tag element being adapted to be folded transversely upon the intermediate contracted portion about a part of an automobile with said ends disposed upon one side of said part, and
10 means for securing the ends together.
15 3. A tag formed of a flexible sheet, said tag having a contracted intermediate portion and end portions extending laterally in one direction only beyond the intermediate portion, said tag being foldable transversely upon the contracted portion about the shank of an automobile door handle with the laterally projecting ends of the tag disposed upon one side of the handle to prevent undue movement of the folded tag, and means for connecting said ends.
